Application November 19, 1942, Serial No. 466,101

10 Claims.

(Cl. 24—153)

The invention relates to filing devices and more particularly to a loose leaf fastener of the type including a base member having bendable prongs to extend through a stack of sheets and be interlocked with a separable compressor member of novel construction.

Prong fasteners including a base having bendable prongs and an associated compressor, such as is disclosed in Kline Patent No. 1,658,052, issued February 7, 1928, are best made of thin sheet steel which is easily and inexpensively fabricated, and which retain their critical dimensions to insure proper functioning of their related movable parts so as to remain useful indefinitely. A critical metal shortage has occasioned the use of substitute materials as fibre, pressboard, cardboard, or the like. These materials are hard and are substantially shape retaining but, because they are porous, they tend to absorb moisture and frequently expand, contract or warp sufficiently to destroy the critical dimensions of the various compressor parts. As a result, any movable parts on a compressor made of such material will operate inefficiently and frequently bind to such an extent as to make them utterly useless for the purpose intended. The selection of substitute materials for the base member is restricted to those materials which may be bent or folded repeatedly without breaking and yet have sufficient toughness to resist tearing under normal conditions to use. Experience has shown that it is impossible to properly retain prongs made of such substitute materials in their ultimate bent down or folded position by known types of metallic compressors.

Certain known types of fasteners made of cardboard, or like stock, lack practical means to retain the compressor tightly against the stack of sheets prior to, and in some instances after, bending and fastening of the prongs. This is because of the inherent tendency of the stack of sheets to resist compression. In known instances where such means may be provided, such as, for example, that shown in my companion application, Serial No. 466,100, filed of even date herewith, difficulty may be encountered in threading the prong through the compressor, particularly if the prong has become even slightly frayed at its end.

The present invention has for its aim the construction and organization of a pronged fastener which effectively overcomes the deficiencies inherent in the fibre, pressboard, cardboard, etc., from which it may be made and certain undesirable characteristics of other known devices; and

one which is not expensive to manufacture but is very efficient in use.

It is therefore an object of the present invention to provide a fastener compressor embodying novel structural features to facilitate the threading of associated prongs therethrough and the movement of said prongs into a position to be wedged tightly in place so as to prevent unintentional separation of the fastener parts.

- 5 10 Another object is to provide a fastener compressor of the character described with finger engaging means to facilitate its being shifted into binding-wedging engagement with associated prongs.
- 15 20 Another object is to provide a fastener compressor with integral wedge-flaps suitably shaped to facilitate easy movement of associated prongs into position for cooperative engagement thereby.
- 25 Another object is to provide a reinforced compressor having simple means to receive and bindingly and wedgingly co-act with an associated member so as to resist any forces tending to cause separation of the parts, and which may be easily and quickly assembled or disassembled.
- 30 35 Another object is to provide an apertured compressor having readily engaged means to bindingly and wedgingly co-act with associated prongs and novel means to retain the prongs in a folded down partially concealed position after assembly to increase the effectiveness of such an engagement.

The foregoing and such other objects of the invention as will appear hereinafter as the description proceeds will be more readily understood from a perusal of the following specification, in which reference is had to the accompanying drawing, wherein:

Fig. 1 is a perspective view of one embodiment of the improved fastener assembled on a file of papers, the file being partially broken away.

Fig. 2 is an enlarged transverse sectional view taken on line 2—2 of Fig. 1.

Fig. 3 is a central longitudinal sectional view of the fastener, showing the base in elevation and one prong partially disengaged.

Fig. 4 is a top plan view of the fastener showing the parts in the relative positions illustrated in Fig. 3.

Fig. 5 is a plan view similar to Fig. 4, showing the compressor in a transversely shifted position relative to the associated prongs.

Fig. 6 is a perspective view of a modified form of compressor, showing one prong engaged therewith.

55 Like reference numerals are used herein to

identify corresponding parts in the various embodiments disclosed.

Referring to the drawing and particularly to Fig. 1, the improved fastener is shown applied to a file folder including cover members 11 and 12 having a stack of sheets 13, to be bound arranged therebetween. The cover members 11 and 12 usually are made of pressboard or the like and each may include a mounting strip 14 hingedly connected thereto by means of flexible binding strips 15 whereby the cover members may be moved freely into open or closed positions to afford access to the fastener and bound sheets.

The fastener illustrated includes a base member 16, best shown in Fig. 3, and a compressor 17 each of which may be formed of any substantially stiff sheet material such as fibre, pressboard, cardboard, or the like. The base 16 is formed of an elongated strip of such material and comprises an intermediate body portion 18 having bendable prongs 19 at its ends preferably of a width substantially less than that of the intermediate portion. Longitudinal ribs 20 may be formed on the bottom face of the intermediate body portion 18 to stiffen it against longitudinal flexing. The base member is applied to the file folder by placing the intermediate body portion 18 against the bottom face of the folder strip 14 and extending the spaced prongs 19 through similarly spaced aligned holes 21 in both strips and the stack of sheets. When thus mounted, the free end portions of the prongs project upwardly beyond the top surface of the top strip 14 as shown.

The compressor 17 preferably is formed from a strip of heavier stock than the base member and is particularly designed to cooperate with the extending end portions of the prongs. Transversely spaced offsets, preferably in the form of longitudinal ribs 22, are provided on the bottom face of compressor 17 to reinforce said strip and to define a longitudinal inverted channel 23 co-extensive with the length of the compressor. The ribs 22 are located closely adjacent to one longitudinal edge of the compressor, thereby providing one marginal flange 24 of less width than the other marginal flange 25.

Suitable openings 26, preferably in the form of transverse slots, are provided in the compressor one adjacent each end and spaced apart a distance substantially equal to the spacing of the prongs. These openings, as best shown in Figs. 4 and 5, are located in the marginal flange 25 and extend transversely inwardly through the adjacent rib 22. Their overall length and width is at least such as will freely admit the extended end portions of the prongs when the latter are threaded therethrough and the compressor moved downwardly against the top face of the cover strip 14.

The inner end of each slot 26 terminates in a transverse slit 27. These slits are spaced apart substantially the same distance as the prong spacing and they align with the longitudinally outer side edge of the respective slots 26, as shown. The slits 27 are of a length substantially equal to the width of the inverted channel 23 and each communicates with a longitudinally inwardly directed slit 28 at each end to define a substantially U-shaped slit at each compressor end. The compressor portions partially surrounded by said slits constitute flaps 29 which normally lie substantially in the plane of the compressor. It will be noted, particularly upon

reference to Figs. 4 and 5, that the corner of each flap 29 adjacent the slot 26 has been removed to increase the effective length of said slots and for a purpose to be better understood when the fastener operation is hereinafter explained.

It should be obvious at this time that, when the compressor is in the initial position shown in Fig. 5 with the prong portions 19 extending through the openings 26, it may be shifted transversely relative to said prongs to locate the prongs in the slits 27. The slits 27 are necessarily of a width narrower than the thickness of the prong material, consequently movement of the prongs transversely therein deflects the flaps 29 and causes them to flex upwardly slightly out of the plane of the compressor as best illustrated in Fig. 3. This flexing of the flaps 29 creates a binding-wedging action on the prongs and prevents unintended movement of the compressor 20 away from the face of the file. Cooperative engagement between the compressor and the prong permits the stack of sheets to be compressed tightly and held prior to final securement of the prong ends.

After the compressor is thus applied the extending end portions of the prongs are folded over inwardly towards each other to overlie the respective flaps 29 (Fig. 4) and are retained in this position upon being extended downwardly, through other compressor openings 31, into the inverted channel 23. This folding over of the prong portions urges the flaps 29 downwardly more tightly against the engaged prongs thus increasing their wedging action. Retention of the compressor is furthered by the distortion or "kinking" of the prongs at the flaps, as at 32.

Finger engagement of the compressor for effecting its transverse shifting is facilitated by upsetting suitable arcuate portions 33 and 34 on the respective marginal flanges 24 and 25.

The fastener compressor illustrated in Fig. 6 is substantially like that form just described except that in this instance the medial compressor portion 35 is elevated to provide an inverted channel 45 for receiving the bent over ends of the prongs 19 after they are inserted through transverse openings 31. Longitudinal spaced ribs 36 extend outwardly from the ends of the raised medial portion 35 to define end channels 37 on the top face of the compressor for receiving the exposed portions of the bent over prongs and protect them against such inadvertent engagement as might tend to pull them out of the respective openings 31. In this embodiment, each transverse slot 26 provided in the marginal portion 25, extends through one of the ribs 36 to connect with its respective transverse slit 27.

Obviously the fastener herein described may be used to bind sheets in a stack without the use of file folders. It should be evident also that the improved fastener is characterized by the absence of any manually movable locking devices, such as slide latches, and consequently is not susceptible to being rendered ineffective should absorption of moisture or other causes result in slight alteration of its various dimensions. Further, the compressor may be removed readily from its association with the prongs by withdrawing the latter from the openings 31 and deflecting them slightly outwardly into a position substantially as illustrated at the left hand side of Fig. 3. This minimizes the binding effect of the flaps and permits the prongs to slide easily through the compressor slits 27.

Although the instant disclosure is concerned

with several specific embodiments of a non-metallic fastening device, it should be understood that this disclosure is by way of illustration only and not by way of limitation, and that the invention may be embodied in fasteners made wholly or in part from metal or may embody various modifications in minor details without departing from the spirit and scope of the appended claims.

I claim:

1. A fastener compressor comprising a flat strip of substantially stiff material, said strip having a substantially U-shaped slit adjacent each end to define flaps normally lying substantially in the plane of said strip, the intermediate portions of said U-shaped slit terminating at one end in an opening of a size to freely receive a prong of an associated base member threaded therethrough, said compressor being adapted to be shifted transversely relative to the prongs to carry the prongs out of the openings and into the complementary intermediate slit portions whereupon the flaps are displaced and the compressor and prongs are held against separation by the binding-wedging action of said flaps, and means on the compressor adapted to retain the prongs bent down over said flaps.

2. A fastener compressor comprising a flat strip of substantially stiff material, said strip having a substantially U-shaped slit adjacent each end each having its leg portions extending longitudinally inwardly towards the other to define longitudinally opposed flaps normally lying substantially in the plane of said strip and its intermediate portion terminating at one end in an opening of a size to freely receive a prong of an associated base member threaded therethrough, said compressor being adapted to be shifted transversely relative to the prongs to carry the prongs out of the openings and into the complementary intermediate slit portions whereupon the flaps are displaced and the compressor and prongs are held against separation by the binding-wedging action of said flaps, and means on the compressor adapted to retain the prongs bent down inwardly over said flaps.

3. A fastener compressor comprising a flat strip of substantially stiff material having a longitudinal channel in its bottom face, said strip having a substantially U-shaped slit adjacent each end each having its leg portions extending longitudinally inwardly towards the other to define longitudinally opposed flaps normally lying substantially in the plane of said strip and its intermediate portion terminating at one end in an opening of a size to freely receive a prong of an associated base member threaded therethrough, said compressor being adapted to be shifted transversely relative to the prongs to carry the prongs out of the openings and into the complementary intermediate slit portions whereupon the flaps are displaced and the compressor and prongs are held against separation by the binding-wedging action of said flaps, and means on the compressor adapted to retain the prongs bent down inwardly over said flaps.

4. A fastener compressor comprising a flat strip of sheet material having spaced apart longitudinal reinforcing ribs on its bottom face, said strip having a substantially U-shaped slit adjacent each end to define longitudinally opposed flaps normally lying substantially in the plane of said strip, the intermediate portions of said slits terminating at one end in an opening of a size to freely receive a prong of an associated base

member threaded therethrough, the prong being relatively thick as compared to the width of the slit, said compressor being adapted to be shifted transversely relative to the prongs to carry the prongs out of the openings and into the complementary intermediate slit portions whereupon the flaps are flexed upwardly and the compressor and prongs are held against separation by the binding-wedging action of said flaps, and means on the compressor adapted to retain the prongs bent down over said flaps.

5. A fastener compressor comprising a flat strip of substantially stiff material having spaced apart longitudinal reinforcing ribs, said strip having a substantially U-shaped slit adjacent each end to define longitudinally opposed flaps normally lying substantially in the plane of said strip and its intermediate slit portion terminating at one end in an opening of a size to freely receive a prong of an associated base member threaded therethrough, said compressor being adapted to be shifted transversely relative to the prongs to carry the prongs out of the openings and into the complementary intermediate slit portions whereupon the flaps are displaced and the compressor and prongs are held against separation by the binding-wedging action of said flaps, and means on the flaps to facilitate movement of the prongs into said slit portions.

6. A fastener comprising a base having spaced bendable prongs arranged against one face of a stack of sheets with its prongs threaded through spaced holes in said stack, a compressor formed of a strip of material which is relatively wide as compared with the width of the prongs, a longitudinal channel in the bottom face of said strip, said channel being spaced closely adjacent one longitudinal edge of the strip and being of a width at least equal to the width of said prongs, the strip having a transverse slit at each end each terminating at one of its ends closely adjacent to the said longitudinal edge and at its other end in a transverse slot, longitudinal slits extending inwardly from each end of said transverse slits to define therewith flaps, the slots being relatively wide as compared with the thickness of the prong material whereby the prongs may be threaded therethrough when the compressor is placed against the other face of said stack, said compressor being shiftable transversely to engage the prongs in the respective slits, and the prongs being bendable inwardly towards each other against the top face of the compressor to urge the flaps into binding-wedging engagement with said prongs at their bends.

7. A fastener comprising a base having spaced bendable prongs arranged against one face of a stack of sheets with its prongs threaded through spaced holes in said stack, a compressor formed of a strip of material which is relatively wide as compared with the width of the prongs, the strip having a transverse slit at each end each terminating at one of its ends closely adjacent to one longitudinal edge of said strip and at its other end in a transverse slot, said transverse slits communicating with longitudinal slits extending inwardly from each of their ends to define therewith flaps, the slots being relatively wide as compared with the thickness of the prong material whereby the prongs may be threaded therethrough when the compressor is placed against the other face of said stack, said compressor being shiftable transversely to engage the prongs in the respective slits, said engagement flexing the flaps to cause them to bindingly engage and

prevent withdrawal of the prongs longitudinally.

8. A fastener compressor comprising a flat strip of substantially stiff material having a longitudinal channel in its bottom face terminating short of the ends of said strip, said strip having a substantially U-shaped slit adjacent each of its ends each having its leg portions extending longitudinally inwardly towards the channel to define longitudinally opposed flaps normally lying substantially in the plane of said strip and its intermediate slit portions terminating at one end in an opening of a size to freely receive a prong having a thickness relatively greater than the width of the slit threaded therethrough, said compressor being adapted to be shifted transversely relative to the prongs to carry the prongs out of the openings and into the complementary intermediate slit portion whereupon the flaps are flexed upwardly and the compressor and prongs are held against separation by the binding-wedging action of said flaps, the channel having open ends through which the prongs may be threaded to hold them bent down inwardly towards each other over the underlying flaps.

9. A fastener compressor comprising a flat strip of substantially stiff material having a longitudinal channel extending inwardly from each end, said strip having a substantially U-shaped slit in the bottom wall of each channel to define longitudinally opposed flaps normally lying substantially in the plane of said bottom wall and its intermediate slit portions terminating at one end

in an opening of a size to freely receive a prong of an associated base member threaded therethrough, said compressor being adapted to be shifted transversely relative to the prongs to carry the prongs out of the openings and into the complementary intermediate slit portions whereupon the flaps are flexed upwardly and the compressor and prongs are held against separation by the binding-wedging action of said flaps, and means on the compressor adapted to retain the prongs bent down into the channels over said flaps.

10. A fastener comprising a base having spaced bendable prongs arranged against one face of a stack of sheets with its prongs threaded through spaced holes in said stack, a compressor formed of a strip of material having a transverse slit at each end terminating at one of its ends in an opening, said transverse slits joining with longitudinal slits extending from each of their ends to define therewith flaps, the openings being of such size as to permit threading of the prongs therethrough freely when the compressor is placed against the other face of said stack, said compressor being shiftable transversely to engage the prongs in the respective transverse slits, and the prongs being bendable down against the top face of the compressor to overlie and urge the flaps into binding-wedging engagement with said prongs at their bends.

EMIL KERN.
